UNITED STATES PATENT OFFICE

147,646

DESIGN FOR A DISPOSAL RECEPTACLE

Irving M. Footlik, Chicago, Ill.

Application February 27, 1946, Serial No. 126,958

Term of patent 3½ years

(Cl. D58—22)

To all whom it may concern:

Be it known that I, Irving M. Footlik, a citizen of the United States, residing at Chicago, in the county of Cook and State of Illinois, have invented a new, original, and ornamental Design for Disposal Receptacles, of which the following is a specification, reference being had to the accompanying drawing, forming part thereof.

Fig. 1 is a top plan view of a disposal receptacle, showing my new design;

Fig. 2 is a front elevational view thereof, and Fig. 3 is a side elevational view thereof.

I claim:

The ornamental design for a disposal receptacle, as shown.

IRVING M. FOOTLIK.
